TOOTHBRUSH

Emanuel Aaron, New York, N. Y.

Application December 15, 1944, Serial No. 568,283

5 Claims. (Cl. 15—172)

1

This invention relates to cleaning implements or instruments and has especial reference to toothbrushes.

An object of the present invention is the provision of improvements in a toothbrush, whereby the brush may be conveniently used to carry out cleaning or brushing operations, and especially up and down brushing movements, on all of the upper and lower teeth and gums in the mouth of the user, in a thorough manner.

A further object of the invention is the provision of a toothbrush in which the cleaning element projects laterally with respect to the handle, and is adjustable to change its angularity while disposed as aforesaid, by the mere manipulation of the parts of the handle with one hand, to the end that the user with the same hand may move the cleaning element up and down against the teeth in each arch at the front and sides of the arch.

A further object of the invention is the provision of a toothbrush of the indicated character having a detachable and replaceable cleaning element or brush section.

With the foregoing, other objects of the invention will appear when the following specification is read in connection with the accompanying drawing, in which,

Figure 1 is a perspective view of a toothbrush embodying the features of the invention, a hand being shown in dotted lines to indicate the manner in which the parts of the handle are manipulated to adjust the angularity of the bristle section of the brush.

Figure 2 is a side view of the brush.

Figure 3 is a side view looking at the brush turned ninety degrees from the position shown in Figure 2.

Figure 4 is an enlarged fragmentary sectional view, the section being taken approximately on the line 4—4 of Figure 3.

Figure 5 is a sectional view taken on the line 5—5 of Figure 4.

Figure 6 is a sectional view taken on the line 6—6 of Figure 2.

Referring now more particularly to the drawing, it will be apparent there is shown a cleaning implement in the nature of a toothbrush including a cleaning element or section 10. The section 10 consists of an elongated head 11 having bristles 12 on one side thereof.

The implement also includes a handle 13 consisting of two elongated parts 14 and 15 respectively. The parts 14 and 15 are substantially of the same length and cross-sectional shape. The

2

parts 14 and 15 as shown are flat and they are made of flexible material, such as a cellulose or plastic composition, or any other suitable material having a degree of flexibility or resiliency so as to bend. Each part 14 and 15 has a bearing 16 on one end. The bearing may be attached or be formed integral with the handle part, as in the present instance. The bearing 16 extends laterally or obliquely with respect to the longitudinal axis of the handle part. Each bearing is in the nature of a sleeve and has longitudinal grooves 17 diametrically opposite each other interiorly thereof, as shown most clearly in Figures 4 and 5.

15 The handle part 14 has a slot 18 therein extending longitudinally near the end remote from the bearing, and a key 19 is formed or otherwise secured to said part 14 near said bearing 16.

The handle part 15 carries a fastening element 20 near the end remote from its bearing. Said element may be a bolt or eyelet 20 of two interfitting members as shown. The handle part 15 also has a groove or keyway 21 extending longitudinally near its bearing 16.

25 The handle parts 14 and 15 are designed and adapted to be laid together flatwise with the eyelet 20 extending loosely in the slot 18 and the key 19 projecting loosely in the keyway 21. The parts 14 and 15 are thus connected for longitudinal

30 movement with respect to each other. In other words, one handle part may be slid with respect to the other part while both parts are held in one hand, the thumb being used to slide the part 14 either in one direction or the other. Each of 35 the parts 14 and 15 has a roughened area 22 to facilitate the manipulation of said parts. The handle parts have limited longitudinal movement by reason of the fastener 20, and the key 19 together with the fastener 20 prevent canting of 40 the parts 14 and 15 with respect to each other.

The head of the brush section 10 has pintles 23 on one end thereof. The pintles are arranged in spaced relation to each other and are parallel to the longitudinal axis of the head 11. The pintles 23 are loosely received in the bearings 16 respectively. Each pintle 23 has a cross-pin 24

45 capable of passing through the grooves 17 when attaching the brush section 10 to the handle, or when detaching the same therefrom. The cross-pins 24 are disposed in recesses 25 respectively in the bearings 16 and engage the bearings to prevent detachment of the brush section 10, while enabling the pintles to turn and also have a small amount of axial movement in the bearings.

55 When the brush section 10 is in a neutral posi-

tion, the pins 24 will be in line with the grooves 17, thereby enabling the detachment of the brush section or its replacement.

On reference to Figure 3 it will be seen the brush section is disposed in an angular position in which it projects to the right at an angle of forty-five degrees, as shown in full lines. When the handle parts 14 and 15 are moved or slid in opposite directions, as indicated by the arrows, or when either part is moved or slid relatively to the other part, the bearings 16 will ride on each other. This is possible due to the flexibility or resiliency of the handle parts. The bearings 16 will assume a reversed relation by reason of the relative movement of the handle parts. This will cause the brush section 18 to rock with the pintle 23 in the bearing 16 of the part 15, while the other pintle 23 operates against its bearing 16 on the part 14. As a consequence the brush section 18 will be moved into a different angular position in which it projects to the left at an angle of forty-five degrees, as indicated in dotted lines in Figure 3. It will be understood the brush section 18 moves ninety degrees from one angular position to the other. The amount of angular movement of the brush section 18 may be more than ninety degrees if desired by originally designing the parts for that purpose.

The bearings 16 are rounded in cross section so as to easily ride on each other. Small depressions 26 in the confronting faces of the handle parts receive the respective bearings 16 to aid in retaining the parts against unintentional movement.

From the foregoing it will be understood the toothbrush may be used with one hand to easily and conveniently impart an up and down movement of the bristle section 18 against the teeth of both arches of the user. The front teeth may be so brushed. Those teeth at the right side of the mouth may be brushed with the brush section 18 cocked to the right, and the teeth at the left side may be brushed with the brush section cocked to the left. The mere manipulation of the handle parts will cock the brush section at the desired angle with respect to the handle according to which teeth are to be brushed, those at the right or left side of the mouth, and also according to whether the implement is held in the right or left hand of the user. By gripping the handle parts the brush section 18 is firmly held in the desired angular position as though it were fixed to the handle.

Having thus described my invention, what I claim as new and desire to secure by Letters Patent is:

1. A toothbrush comprising a head having bristles on one side thereof, a handle consisting of two parts connected side by side so that the

parts may be slid longitudinally relatively to each other, said handle parts having bearings on adjacent ends thereof respectively, said head having spaced pintles which are loosely received in said bearings respectively, the provision and arrangement being such that the head may be disposed in different angular positions with respect to the handle upon relative movement of the handle parts, and said head being retained in the desired angular position by gripping the handle parts together.

2. A toothbrush as set forth in claim 1, wherein each of said bearings has a longitudinal groove therein, and each of said pintles has a cross pin at one end movable in the groove of the related bearing to attach the head to and detach it from the handle, said cross pin being engageable with the related bearing to aid in retaining the head attached to the handle and enabling the pintle to rotate and also have limited axial movement with respect to its bearing.

3. A toothbrush as set forth in claim 1 wherein said bearings are disposed at an angle to the respective handle parts and in parallelism to each other.

4. A toothbrush comprising an elongated head having cleaning bristles on one side thereof, a handle consisting of two elongated parts having flat surfaces confronting each other, means connecting said handle parts so that they may be moved longitudinally relatively to each other, said handle parts having bearings on adjacent ends respectively and projecting laterally, said head having spaced pintles on one end thereof in parallel relation and loosely received in said bearings respectively, and coacting means on the bearings and pintles whereby the pintles may turn and also have limited axial movement in said bearings, the provision and arrangement being such that one handle part may be moved longitudinally with respect to the other, to thereby change the position of the head with respect to the handle through the intervention of the pintles and bearings, and said head being held in the set position by gripping the handle parts.

5. A toothbrush comprising a head having bristles on one side thereof, a handle consisting of two parts spaced side by side and connected so that said parts may be moved longitudinally relative to each other, said handle parts each having a transverse bearing arranged side by side on adjacent ends of said parts and the head having longitudinally extending pintles at one end which are loosely received in said bearings, so that when said parts are moved longitudinally with relation to each other said head can be adjusted about its longitudinal axis.

EMANUEL AARON.
